(57) CLAIM

The ornamental design for a camera, as shown and described.

DESCRIPTION

The present application is related to U.S. patent application Ser. No. 29/530,171, issued as U.S. Design Pat. No. D775, 684, entitled “Stand Assembly,” filed on Jun. 14, 2015; U.S. patent application Ser. No. 29/530,170, issued as U.S. Design Pat. No. D807,948, entitled “Receiving Element of a Stand Assembly,” filed on Jun. 14, 2015; and U.S. patent application Ser. No. 29/530,169, issued as U.S. Design Pat. No. D800,824, entitled “Camera Stand Base,” filed on Jun. 14, 2015, each of which is hereby incorporated by reference in its entirety.

FIG. 1 is a perspective view of a camera showing our new design.

FIG. 2 is a front elevation view of the camera shown in FIG. 1.

FIG. 3 is a rear elevation view of the camera shown in FIG. 1.

FIG. 4 is a side view of the camera shown in FIG. 1.

FIG. 5 is a top plan view of the camera shown in FIG. 1; and, FIG. 6 is a bottom plan view of the camera shown in FIG. 1.

The broken lines depicting portions of a camera in the above described figures form no part of the claimed design. The broken lines showing base structures in FIGS. 1-6 represent environmental structures that form no part of the claimed design.
